ELECTRIC LIGHT

Filed Jan. 11, 1932

UNITED STATES PATENT OFFICE

BURTON S. FLORADAY, OF TOLEDO, OHIO, ASSIGNOR TO THE DURA COMPANY, OF TOLEDO, OHIO, A CORPORATION OF OHIO

ELECTRIC LIGHT

Application filed January 11, 1932. Serial No. 586,050.

This invention relates generally to lights and refers more particularly to lights of the self-contained portable unit type adapted to be supported in a holder upon a wall or other upright member.

One of the essential objects of the invention is to provide a light wherein a switch at the lower end of a battery casing is adapted to be operated by a part of the holder to control the illumination of a bulb at the upper end of the battery casing when the light is received within the holder.

Another object is to provide a light wherein the switch referred to is operable automatically when the light is removed from the holder to close the circuit to the light bulb so that the bulb will be illuminated when the light is carried in the hand.

A further object is to provide a light wherein the switch may be operated manually after the light is removed from the holder so that the support to the light bulb will be opened and will remain open regardless of whether the light is carried by hand or is returned to the holder.

A further object is to provide a light wherein the cup thereof is provided with a pivotal ring that is in an inoperative out of the way position about the reduced portion of the cup when the latter is within the holder but is capable of being swung outwardly to an operative supporting position after the cup aforesaid has been removed from the holder.

A further object is to provide a pivotal ring which is associated with the cup in such a way that it is capable of supporting the light in raised position in the holder above the stud 27 whereby the circuit to the bulb may remain closed while the light is in the holder.

Other objects, advantages and novel details of construction of this invention will be made more apparent as this description proceeds, especially when considered in connection with the accompanying drawing, wherein:

Figure 1 is a front elevation of a light mounted in a holder on a wall;

Figure 2 is a vertical sectional view

through the structure illustrated in Figure 1;

Figure 3 is a fragmentary vertical sectional view of the holder and the light just before the light is received within the holder;

Figure 4 is a fragmentary vertical section 55 view of the light and showing the movable contact element held in inoperative position by means of the button;

Figure 5 is a bottom plan view of the light; 60

Figure 6 is a fragmentary vertical sectional view through the light and holder showing the position of the light in the holder when the ring is inclined relative to the bottom of the cup. 65

Referring to the drawing, A is a light of the self-contained portable unit type, and B is a holder therefor. As shown, the light A preferably comprises a tubular casing 1, an electric light bulb 2 having its terminal 3 anchored within the upper end 4 of the casing, an electric battery 5 within the casing and preferably comprising two dry cells, and an electric switch unit C at the lower end of the casing. Preferably this unit C includes a cup 6 threadedly engaging the lower end of the casing 1 and having a reduced end portion 6', a ring 6" pivoted to the cup 6 and adapted to encircle the reduced portion 6' of the ring, a disc 7 of insulating material fixed 70 in the cup 6 in spaced relation to the bottom 8 thereof, a coil spring 9 on the disc 7 and holding the battery 5 against the bulb terminal 3, a strip 10 of sheet metal anchored on the disc, having tongues 11 holding the lower convolution 12 of the spring and having a prong 13 extending downwardly through the disc 7, and a spring metal strip 14 secured to the prong 13 on the underside of the disc 7 and having a free end 15 urged downwardly 75 and provided with a depending lip portion 16 that is engageable with the bottom 8 of the cup to close the circuit to the bulb 2. Thus in this construction the strip 14 constitutes the movable electric contact element, while the bottom 8 of the cup constitutes the stationary element. Preferably the strip 14 is

provided intermediate its ends with a depending transversely extending corrugation 17 and the bottom 8 of the cup is provided below 80 100

said strip in vertical alignment therewith with a key hole slot 18. A suitable manually operable button 19 of insulating material is 5 slidable in the narrow portion 20 of this slot and is engageable with the corrugation 17 to raise the lip 16 from the bottom 8 of the cup and cause the circuit to the bulb 2 to be opened. Any suitable means such as the crimped edge portions 20' and 20'' of the narrow portion 20 of the slot may be utilized for holding the button in said narrow portion 20 while in use. Preferably the construction of the button 19 is such that the lip 16 may bear against the bottom 8 of the cup 15 and close the electric circuit to the bulb 2 when the button 19 is upon either side of the corrugation 17. It is only when the button 19 is directly below the corrugation 17 that the lip 16 is disengaged from the bottom 8 of the cup and the circuit to the bulb 2 is open.

The holder B preferably comprises a bracket 20 having an upright strip portion 21 attachable to the wall 22 or other suitable support and having a curved base portion 23, a shelf 24 fastened by a rivet 25 to the curved base portion 23, a cup-shaped body 26 fastened by the rivet 25 to the shelf 24, and a stud 27 of insulating material rigid with the rivet 25 and projecting above the bottom 28 of the cup-shaped body 26.

In use the button 19 may be moved longitudinally of the slot 18 to one side or the other of the corrugation 17 to permit the lip 16 to engage the bottom 8 of the cup and thereby close the circuit to the bulb 2, or may be moved under the corrugation 17 to cause the lip 16 to be raised from the cup bottom 8 so that the circuit to the bulb 2 will be opened. Should the light A with the button 19 at one side or the other of the corrugation 17 be inserted into the cup-shaped body 26 of the holder B, the stud 27 will be received in the slot 18 and will abut the corrugation 17 with the result that the lip 16 will be raised from the cup bottom 8 and the circuit to the bulb 2 will be opened. When the light A is removed from the holder B the stud 27 will be disengaged from the corrugation 17, consequently the lip 16 will engage the cup bottom 8 and will again close the circuit to the bulb 2. While out of the holder the button 19 may be moved into engagement with the corrugation 17 to cause the lip 16 to be disengaged from the cup bottom 8, and should the light then be returned to the holder B, the button 19 will abut the upper end of the stud 27 but will not be moved thereby, consequently the switch parts will remain in the open position in which they were before the light A was placed in the holder B. However, when the button 19 is at one side or the other of the corrugation 17 and the ring 6'' is inclined relative to the bottom 8 of the cup 65 and the light is placed within the holder, as

illustrated in Figure 6, the corrugation 17 will be spaced above the upper end of the stud 27, consequently the lip 16 will remain in contact with the bottom 8 of the cup and the circuit to the bulb 2 will remain closed. When the light A is removed from the holder the ring 6'' may be utilized as a support for the light.

What I claim as my invention is:

1. In a light of the self-contained portable unit type, a member of insulating material, an electric switch contact element carried by said member, a support for said member having an opening in line with the element whereby a part of a holder for the light may extend through the opening and actuate the element, and actuating means for the element including a manually operable button of insulating material movable in the opening and capable of assuming a position for rendering the holder part aforesaid inoperative for actuating the element.

2. A light of the self-contained portable unit type adapted to be supported in a holder, and having an end provided with an opening forming a guide for a control button and adapted to receive a projection of the holder, and a movable electric switch contact element in alignment with the opening and having a portion alternately engageable by the button and projection.

3. A light of the self-contained portable unit type adapted to be supported in a holder and including a battery spring receiving cup provided in the bottom thereof with a slot that forms a guide for a control button and is adapted to receive a projection of the holder, and a movable switch contact element in rear of the opening and actuatable alternately by the projection and button.

4. A light of the self-contained portable unit type adapted to be supported in a holder and including an end piece having an opening forming a guide for a control button and adapted to receive a projection of the holder, and a movable switch contact element in rear of the opening, engageable with the end piece to close the circuit, and movable away from the end piece by either the button or projection to open the circuit.

5. In a light of the self-contained portable unit type adapted to be supported in a holder, including a battery spring receiving cup having a base provided with an opening forming a guide for a control button and adapted to receive a projection of the holder, a member of insulating material within the cup in spaced relation to the base of the cup, and an electric switch contact element carried by said member and engageable with the base of the cup to close the battery circuit, said element being adjacent the opening so that it may be moved away from the base by either the button or projection to open the battery circuit.

6. In a light of the self-contained portable unit type, an electric switch unit including a disc of insulating material constituting a battery spring support, anchorage means for the battery spring mounted upon one side of the disc and including a strip of metal having struck-out tongues for holding a convolution of the spring, and having another struck-out portion extending through the disc, and a separate electric switch contact element carried by said last mentioned struck-out portion and having a free end movable toward and away from the disc.

7. A light of the self-contained portable unit type adapted to be received in a holder and having an end piece provided with a slot forming a guide for a control button and adapted to receive an upstanding projection of the holder, a movable contact element engageable with the end piece to close a circuit and arranged in line with the slot so as to be moved by either the button or projection to open the circuit, and means associated with the end piece and holder for rendering the projection inoperative so that the circuit will remain closed while the light is in the holder.

8. A light of the self-contained portable unit type adapted to be received in a holder and having an end piece provided with a slot forming a guide for a control button and adapted to receive an upstanding projection of the holder, a movable contact element engageable with the end piece to close a circuit and arranged in line with the slot so as to be moved by either the button or projection to open the circuit, and a member connected to the end piece and engageable with the holder upon insertion therein of the light to render the projection inoperative so that the circuit will remain closed.

9. A holder for lights of the self-contained portable unit type including a bracket having an upright strip portion attachable to a wall and having a base portion, a shelf upon the base, a cup-shaped body upon the shelf, a rivet extending through the base, shelf and body, and a stud of insulating material rigid with the rivet and projecting above the bottom of the cup-shaped body.

10. A light of the self-contained portable unit type adapted to be received in a stationary holder and having a cup-shaped end piece provided in the base thereof with a slot forming a guide for a control button and adapted to receive an upstanding projection of the holder, a movable contact element within the end piece and engageable therewith to close a circuit, said element being arranged in such a way relative to the slot that it may be moved away from the end piece by either the button or the projection aforesaid to open the circuit, and means for rendering the projection inoperative when the end piece is placed in the hold-

er, including a supporting ring for the light connected to the end piece and extending at substantially an acute angle from the bottom of the holder.

11. A light of the self-contained portable unit type adapted to be supported in a holder and having a battery spring receiving cup provided at the bottom thereof with a slot that forms a guide for a control button and is adapted to receive a projection of the holder, a control button movable in the slot, and an electric contact element in the cup in rear of the slot and actuatable alternately by the projection and button.

12. A light and holder combination, including a holder having a projection, and a light of the self-contained portable unit type having a battery spring receiving cup engageable with the holder and provided at the bottom thereof with a slot that forms a guide for a control button and is adapted to receive the projection of the holder, an electric switch contact element within the cup in rear of the slot and actuatable by the projection, and a control button movable within the slot for actuating the contact element and for rendering the projection aforesaid inoperative.

13. A light and holder combination, including a holder having a projection, and a light of the self-contained portable unit type having a battery spring receiving cup engageable with the holder and provided with a slot that forms a guide for a control button and is adapted to receive the projection of the holder, a control button movable in the slot, and an electric contact element in the cup in rear of the slot and actuatable alternately by the projection and button.

14. A light and holder combination, including a holder having a projection, a light of the self-contained portable unit type engageable with the holder and having an opening forming a guide for a control button and adapted to receive the projection of the holder, a control button movable in the slot, an electric contact element in alignment with the slot and alternately engageable by the button and projection.

15. A light of the self-contained portable unit type having a casing adapted to be supported in a holder and provided with a slot that forms a guide for a control button and is adapted to receive a projection of the holder, and a movable electric switch contact element in alignment with the slot and having a portion alternately actuatable by the button and projection.

In testimony whereof I affix my signature.

BURTON S. FLORADAY.
